UNITED STATES PATENT OFFICE.

ELIJAH F. SPAULDING, OF BROOKLYN, NEW YORK.

VENDING-MACHINE.

1,148,807.

Specification of Letters Patent.

Patented Aug. 3, 1915.

Application filed December 28, 1914. Serial No. 879,244.

To all whom it may concern:

Be it known that I, ELIJAH F. SPAULDING, a citizen of the United States, and resident of Brooklyn, in the county of Kings and State of New York, have invented certain new and useful Improvements in Vending-Machines, of which the following is a specification.

This invention pertains to improvements in coin controlled vending machines, and has for its objects to provide simple and efficient means to permit vendible articles to be delivered upon the insertion of a proper coin and the operation of devices controlled by such coin.

The invention further comprises novel details of improvement and combinations of parts that will be more fully hereinafter set forth and then pointed out in the claims.

Reference is to be had to the accompanying drawings forming part hereof, wherein,

Figure 1 is a rear elevation of my improved vending machine, parts being removed; Fig. 2 is a vertical section substantially on the line 2, 2, in Fig. 1, illustrating a coin in position beyond the section line and the machine ready for operation; Fig. 3 is a similar view showing the parts in operated position, and the ejecting lever or arm locked by the weight after the deposit of a lowermost article of a stack; Fig. 3^a illustrates a detail hereinafter referred to; Fig. 4 is a plan view of the controlling mechanism, parts being omitted; Fig. 5 is a detail section substantially on the line 5, 5, in Fig. 4; Fig. 6 is an enlarged detail plan view of member 16; Fig. 7 is a detail hereinafter referred to; Fig. 8 is a front view, the casing being removed; Fig. 9 is a front elevation of plate 32; Fig. 10 is a detail section, and Fig. 11 is a detail section.

Similar numerals of reference indicate corresponding parts in the several views.

The numeral 1 indicates a suitable casing or frame having chutes 2, of any suitable construction, adapted to contain articles 3 to be vended, and at 4 are weights adapted to slide in said chutes and to rest upon the articles 3. Ledges 5 at the bottom of each chute retain the lowermost article, the rear and front portions of the chute being open to admit the lowermost article to be delivered, as at 3^a, in a well known manner. In the form illustrated, the articles as de-

livered are adapted to pass down a passage 6 in the casing to rest upon an exposed supporting surface 7. At 8 is a coin slot for each set of the delivery devices that may be provided in the machine. Within the casing is a somewhat open frame 9 of any suitable construction, which, in the example illustrated, is shown provided with inturned ledges 9^a at its top upon which the chutes rest, said chutes being shown provided with lugs 2^a passing through openings in the ledges 9^a whereby the chutes are supported, although the chutes may be supported in any well known manner. The frame 9 is detachably supported in the casing upon shoulders 1^a thereof (Fig. 1), upon which the frame 9 rests, whereby said frame may be slid into and from the casing through the rear door 1^b, which may be secured to the casing in any suitable manner. Upon the side members of frame 9 a rock shaft 10 is journaled, upon which shaft a weighted stop 11 is secured, shown adapted to engage a rear bar 9^b of frame 9 to retain said shaft in normal position.

Upon shaft 10 one or more levers or arms 12 are pivotally supported respectively beneath the chutes 2, and suitably spaced apart according to whether two or more chutes and delivery devices are provided in one casing. Where the machine is provided with a single chute and coin slot, one of the levers 12 will suffice, two of such levers and associate parts being shown in the accompanying drawing. The levers 12 are so hung that they normally rest at their upper portions 90 against the bar 9^a of frame 9, and such upper portions of said levers are shown normally substantially at one side of the vertical plane of the rear of chute 2. The levers 12 are adapted to pass under the corresponding chute to push the lowermost article from such chute through its opening 3^a when the lever is caused to rock forwardly by a coin interposed between such lever and devices controlled by a push rod or the like 13. For this purpose I have shown the upper ends of levers 12 each provided with an ejector 14 having the projecting portion 14^a adapted to engage the lowermost article of a corresponding stack to eject the same. Ejectors 14 are shown pivotally supported upon pins or the like 15 carried by the levers 12, said ejectors having ears 14^b receiving said pins,

which ejectors are suitably slotted at 14^c (Fig. 8) to receive levers 12, whereby said ejectors are retained from lateral movement upon said levers and are adapted to swing thereon. In their normal positions said ejectors may rest against the levers to retain the projections 14^a behind the lowermost articles, and said projections 14^a of said ejectors, after ejecting an article, are adapted to bear against and tilt under the lowermost article of the corresponding stack, as said ejectors are carried rearwardly by the levers. When the lowest or last article of a stack has been ejected, and weight 4 rests upon the ledges 5, a projection 4^a of said weight will be brought into position to engage a projection 12^b of the corresponding lever 12 (Fig. 3) to prevent said lever 12 from returning to normal until said weight is removed.

The means I have shown for operating the levers 12 are as follows: The lower ends 12^a of levers 12 normally rest above an inclined coin-receiving sliding member 16, to which the push rod 13 is secured, as to the part 16^c, which rod slides freely through a suitable guide or the like in the front wall of casing 1. Said member is shown guided by means of rollers 17, carried upon lugs at the ends of said members, adapted to travel in guiding slots 18 in the side walls or plates of frame 9, said rollers and the rod 13 maintaining frame 16 in proper sliding position within frame 9. Member 16 is provided with an opening 16^a beneath each lever 12 for the passage or deposit of a coin therethrough, which opening is wider than the diameter of a proper coin. The proper coin 19 is to be delivered upon the inclined 40 surface of member 16 to slide thereon and be temporarily retained beneath the corresponding lever 12, as indicated at 19 in Fig. 2. For such purpose I have shown member 16 provided with guideways 22 shown 45 formed between spaced members 20 and 21 on frame 16 (Fig. 6). The member 21 may be a magnet to attract a spurious token upon guideway 22 through an opening 23, in member 16 to dislodge such token and 50 prevent it from passing under lever 12.

To temporarily retain coins under levers 12 in order to operate the corresponding lever 12 when member 16 is pushed inwardly, I provide stops 23, 24 (Figs. 1 and 55 6) on member 16 on opposite sides of the openings 16^a, said stops being so spaced apart as to prevent a coin sliding between them, to temporarily retain such coin above the corresponding opening 16^a, flatwise under the corresponding lever 12. At least 60 one stop of each pair, such as 24, is preferably adjustable, and is shown in the form of a screw meshing in a threaded opening in frame 16, whereby the head of the screw 65 may be raised or lowered to regulate the

passage thereunder of a coin of proper thickness into position between a pair of stops 23, 24.

Upon member 16 is a transversely slideable coin retainer shown in the form of a plate 25, having a lateral or upwardly disposed coin retaining arm 25^a for each opening 16^a. Said members are shown slotted at 25^b and receiving the screws 24, whereby said members are retained and guided. Said members 25^a are so located that, in their normal positions, they overlap a lateral edge of the corresponding opening 16^a, thereby reducing the normal working area of such openings, whereby the coins may 80 rest upon the material at the edges of such openings, partly upon the frame 16 and partly upon the projections 25^a (Figs. 1 and 6). In such position of the parts a coin 19 may be retained beneath an arm 12^a of a 85 lever 12 (Fig. 2), whereby when frame 16 is pushed inwardly by push rod 13, the coin will engage the arm 12^a and tilt the lever, whereupon the projection 14^a of ejector 14 will engage the lowermost article 90 of the corresponding stack and eject it (Fig. 3). A spring 26, by engagement with a pin 27 on member 16 engaging a projection 28 on retainer 25, normally maintains retainer 25 pushed to the left in Fig. 6, in engagement with one or more stops 24. Member 16 is shown pivotally connected, by a pin 16^c (Figs. 2 and 3), with a forked or slotted part 11^a of weighted arm 11, whereby when member 16 is pushed inwardly, shaft 10 will 100 be rocked and weight 11 lifted, so that when push rod 13 is released said weight will cause the member 16 to return to normal, the shoulder 11^b of said weight then resting upon bar 9^a of frame 9.

To operate the coin retainer 25, upon the return stroke of member 16, I have shown said retainer provided at one end with a dog 29, shown pivoted to retainer 25 at 30, which dog is adapted, when retainer 16 is 110 pushed inwardly, to ride up and beyond an inclined projection 31 secured on frame 9, the inner face of which projection is forwardly inclined at 31^a (Fig. 7), whereby on the return stroke of member 16 the dog 29 115 will engage said inclined face 31^a and by riding along the same will cause retainer 25 to slide laterally to withdraw its projections 25^a from beneath any coin or coins on member 16, to permit such coin or coins 120 to pass through the corresponding opening 16^a to a suitable receptacle 7 beneath the mechanism (Fig. 2). As soon as the dog 29 passes beyond projection 31, spring 26 will cause retainer 25 to resume its normal 125 position.

Any suitable means may be provided for guiding the coins from slots 8 to the guideways 22 on member 16. I have shown a plate 32 normally located adjacent to the 130

front plate or wall 9^c of frame 9 and guided to slide on said frame by means of lugs or the like 32^a resting on the edges 9^f of frame 9. Stops 32^c on plate 32 retain said plate normally spaced from wall 9^c providing space *a* for the passage of coins and tokens. Plate 32 is shown provided with openings at 32^b opposite each guideway 22 of member 16 (Fig. 1) to permit the entrance of coins to said guideway. Member 16 is shown provided with prongs or projections 16^d adapted to pass through the openings 32^b of plate 32 into the path of coins from slots 8 when the parts are in their normal positions, to 10 guide said coins upon the guideways 22 of member 16, as shown in Fig. 2. To assure that the coins will not pass down through space *a*, but will be lodged upon the projections 16^d to be guided thereby into the openings 32^b, said projections are sufficiently long to pass across the space *a* (Fig. 2). For such purpose I have shown front plate 9^c of frame 9 provided with openings 9^d to receive the projections 16^d (Figs. 2 and 8). 15 Member 16 is shown as movable relatively to plate 32, and is adapted to move said plate with it, to assure withdrawal of projections 16^d from space *a* when member 16 is first moved, to prevent coins from then 20 being retained upon the projections 16^d during operations of the machine, which coins can then pass below and will be guided by ways 33 (Figs. 1, 2 and 3), downwardly to a coin or token outlet 34 of the casing, to 25 be returned to the customer. I have shown member 16 provided with projections 16^e at its forward corners, to engage lugs or projections 32^a on the inner side of plate 32, the last named projections being so spaced from 30 plate 32 that the projections 16^e may move freely therebetween, and when member 16 is sufficiently pushed inwardly the plate 32 will be carried with it by said projections. Plate 32 will be pushed outwardly with 35 member 16 on the return stroke, by the engagement of member 16 or its projections 16^e with said plate.

Upon plate 32, in vertical alignment with the corresponding guideways 22 of member 50 16, fingers 35 are pivotally supported at 36, upon brackets 37 on said plate. Fingers 35 are provided each with a projection 35^a adapted to extend through a corresponding slot 32^d in plate 32 into space *a*. The projections 35^a, in the normal position of plate 32, project directly beneath the corresponding coin slot 8 in the path of coins through space *a*, so that when a coin drops into said space from a slot 8, said coin will engage a 55 projection 35^a and tilt finger 35, to enable such coin to pass to the projection 16^d below, and thus be guided through the corresponding opening 32^b of the plate 32 to the corresponding guideway 22. The fingers 35 are weighted to normally rest upon stops 38 60 on plate 32 (Figs. 2 and 3) with the projections 35^a extending through slots 32^d respectively. The fingers 35 also have projections 35^b above projections 35^a, and adapted, when the fingers are tilted, to pass through openings 32^d of plate 32 respectively. When a finger 35 is in the normal position shown in Fig. 2, and a light-weight token is passed through slot 8, which is not sufficiently heavy to tilt finger 35 out of its path, said finger 70 will deflect such token and cause it to pass below through space *a* and out through the outlet 34. If a token having a hole in it, such as a washer, but of sufficient weight to tilt finger 35, be inserted through a slot 8, 75 such token will tilt the finger 35 beneath said slot, and cause the upper finger 35^b to enter the hole in the token by reason of the impetus given the finger by the stroke of the token on the projection 35^a, thereby temporarily retaining such token on finger 35^b, to prevent such token from reaching the projections 16^d, so that when member 16 and plate 32 are next pushed inwardly, and the projections 16^d are withdrawn within or 80 behind plate 32 (Fig. 3), such token will be caused to drop below through space *a* and out through opening 34. The distance between the plate 9^c and the ends of projections 35^a and 35^b, when a proper coin engages projection 35^a, is such that the coin can slide between plate 9^c and said projections, as illustrated in Fig. 11. If a token that is adapted to be attracted magnetically 85 be passed through a slot 8, (which token is 90 of such weight as to operate the corresponding finger 35 in the manner of a proper coin), said token, if it passes into guideway 22, will immediately be attracted by the magnet 21 and be drawn to one side to pass 95 through opening 23, to prevent such token from passing beneath the corresponding lever 12.

Each lever 12 is shown provided with a projection 12^d extending forwardly in position over finger 35, and normally in such position as to permit the corresponding finger 35 to tilt, to permit the passage past the finger of a proper coin, but said projection 12^d is in such position that if a washer tilts 100 finger 35 so that the projection 35^b enters the hole in the washer, the latter will be caught upon such finger and there temporarily retained because finger 35 will then engage projection 12^d and prevent said finger from tilting sufficiently to release the washer, the finger then riding under projection 12^d when plate 32 is pushed inwardly, the washer being caused to fall below by 105 reason of the reciprocation of plate 32. The 110 position of projection 12^d, also, is such that when lever 12 is retained in the forward position by the projection 4^a of weight 4, (Fig. 3) the corresponding finger 35, if 115 tilted by a coin or washer, will engage said 120 125 130

projection and one or the other of the projections 35^a, 35^b will obstruct such coin or washer, whereby such coin or washer will be directed to one side of projection 16^a in 5 the space *a*, to fall away below and pass out of opening 34.

If a coin or token of sufficient weight to tilt finger 35, but not of the proper thickness or diameter to be retained between the 10 corresponding pair of stops 23, 24 on member 16, reaches the corresponding guideway 22, (and if it is not attracted by the magnet), it will slide freely between said stops and pass off the rear end of member 16 into 15 a chute leading to the token outlet 34 (Fig. 2). Chute *c* may be secured upon the rear wall of coin receptacle *b*, and said receptacle may be removably retained in casing 1 by means of side projections on said chute entering grooves 1^a in the side walls of said casing, or in any other suitable or well-known manner.

Changes may be made in the details of construction and arrangements of parts 25 shown and described, as the same may be varied, within the scope of the appended claims, without departing from the spirit of the invention.

Having now described my invention what 30 I claim is:—

1. In a vending machine, the combination of a lever, a member opposed to the lever and movable relatively thereto, said member being provided with means to retain a coin 35 flatwise between said member and lever, retaining means for the coin movable independently of said member, and means to move said movable means from a coin during a stroke of said movable member, and 40 means to guide a coin to such position.

2. In a vending machine, the combination of a lever, a member movable relatively thereto, said member being provided with an opening and with means to retain a coin 45 flatwise opposed to the opening between said member and lever, means to guide a coin to such position, and means to release a coin from said member upon the return stroke of said member.

3. In a vending machine, the combination of a lever, a member movable relatively thereto, said member having an opening and spaced stops on opposite sides of the opening, means to retain a coin opposed to said lever to operate the latter upon one movement of the member, and means to release the coin from said stops and member upon its return stroke.

4. In a vending machine, the combination 60 of a lever, a member movable relatively thereto and having an opening, said member having spaced stops on opposite sides of the opening, means to retain a coin opposed to said lever to operate the latter upon one

movement of the member, said means being 65 upon and movable relatively to said member, and means to actuate the last named means to release the coin therefrom upon the return stroke of the member.

5. In a vending machine, the combination 70 of a lever, a member opposed and movable relatively thereto, said member having an opening for depositing coins and having spaced stops on opposite sides of said opening, a coin retainer movable relatively to 75 said member and having a portion normally obstructing the passage of a coin through said opening to retain a coin opposed to the lever on one movement of said member, and means to withdraw said retainer from said coin upon the reverse movement of said member.

6. In a vending machine, the combination 80 of a lever, a member opposed and movable relatively thereto, said member having an opening for depositing coins and having spaced stops on opposite sides of said opening, a coin retainer movable relatively to 85 said member and having a portion normally obstructing the passage of a coin through 90 said opening to retain a coin opposed to said lever on one movement of said member, means to guide said retainer upon said member, means to hold said retainer in normal position, a projection, and means coactive 95 between said retainer and said projection to move said retainer relatively to said opening upon another stroke of said member.

7. In a vending machine, the combination 100 of a lever, a member opposed and movable relatively thereto, said member having an opening for depositing coins and having spaced stops on opposite sides of said opening, a coin retainer movable relatively to 105 said member and having a portion normally obstructing the passage of a coin through said opening to retain a coin opposed to the lever on one movement of said member, means to guide said retainer upon said member, means to hold said retainer in normal 110 position, a projection having an inclined portion, a dog pivotally carried by said retainer to engage said projection, said dog being adapted to freely pass said projection on one stroke of said member and to engage said projection to actuate said retainer on the return stroke of said member.

8. In a vending machine the combination 115 of a lever, a member opposed and movable relatively thereto, said member having an opening for depositing coins and having spaced stops on opposite sides of said opening, one of said stops being adjustable relatively to said member, a coin retainer movable relatively to said member and having a portion normally obstructing the passage of 120 a coin through said opening to retain a coin opposed to the lever on one movement of

said member, and means to withdraw said retainer from said coin upon the reverse movement of said member.

9. In a vending machine, the combination 5 of a lever, a member opposed and movable relatively thereto, said member having an opening for depositing coins and having spaced stops on opposite sides of said opening, a coin retainer comprising a plate mov- 10 ably guided upon said member and having a retaining arm normally obstructing said opening, and means to withdraw said arm from a coin upon a stroke of said member.

10. In a vending machine, the combina- 15 tion of a lever, a member opposed and movable relatively thereto, said member having an opening for depositing coins and having spaced stops on opposite sides of said opening, a coin retainer comprising a plate mov- 20 ably guided upon said member and having a retaining arm normally obstructing said opening, said arm having a slot receiving one of said projections, and means to withdraw said arm from a coin upon a stroke of 25 said member.

11. In a vending machine, the combina- 30 tion of a frame, a shaft, means to retain said shaft in normal position, a lever movably carried upon said shaft, a member opposed to said lever, means upon the frame to guide said member for reciprocation, means to operate said member, said member having means to retain a coin flatwise opposed to said lever to actuate the latter by such coin 35 upon one stroke of the member, and means to release the coin upon the return stroke of the member.

12. In a vending machine, the combina- 40 tion of a frame, a shaft, means to retain said shaft in normal position, a lever movably carried upon said shaft, a member opposed to said lever, means upon the frame to guide said member for reciprocation, means to operate said member, said member having 45 means to retain a coin flatwise opposed to said lever to actuate the latter by such coin upon one stroke of the lever, means to release the coin upon the return stroke of the member, and means coactive between said 50 shaft and member for operating the shaft with said member.

13. In a vending machine, the combina- 55 tion of a lever, means to pivotally support the same, a member movable relatively to the lever, means upon the member to retain a coin in operative relation to the lever, and a plate adjacent to said member and provided with an opening, said member having a projection adapted to pass through 60 said opening to direct a coin upon said member.

14. In a vending machine, the combina- 65 tion of a lever, means to pivotally support the same, a member movable relatively to

the lever, means upon the member to re- 65 tain a coin in operative relation to the lever, a plate adjacent to said member and provided with an opening, said member having a projection adapted to pass through said opening to direct a coin upon said member, 70 said member having movement relatively to said plate to permit withdrawal of said projection from beyond said plate, means to cause said plate to move with said member.

15. In a vending machine, the combina- 75 tion of a lever, means to pivotally support the same, a member movable relatively to the lever, means upon the member to retain a coin in operative relation to the lever, a plate adjacent to said member and provided 80 with an opening, said member having a projection adapted to pass through said opening to direct a coin upon said member, said member having movement relatively to said plate to permit withdrawal of said projec- 85 tion from beyond said plate, means to cause said plate to move with said member, a frame having a wall spaced from said plate for the passage of coins therebetween, said projections normally extending into said 90 space to intercept coins.

16. In a vending machine, the combina- 95 tion of a lever, means to pivotally support the same, a member movable relatively to the lever, means upon the member to retain a coin in operative relation to the lever, a plate adjacent to said member and provided with an opening, means to direct a coin upon the member through said opening, a finger movably carried by said plate above said 100 member and having a portion adapted to engage a coin, said lever having a projection to engage said finger to cause the latter to intercept a coin when the lever is in operated position.

17. In a vending machine, the combina- 105 tion of a lever, means to pivotally support the same, a member movable relatively to the lever, means upon the member to retain a coin in operative relation to the lever, a 110 plate adjacent to said member and provided with an opening, means to direct a coin upon the member through said opening, a finger movably carried by said plate above said member and having a projection adapted to pass through an opening in said plate, said 115 lever having a projection adapted to limit movement of said finger when the lever is in operated position.

18. In a vending machine, the combina- 120 tion of a frame having a wall, a lever piv- 125 otally carried by said frame, a member movable relatively to said frame and opposed to said lever, said member having means to retain a coin in position to operate said lever, a plate between said wall and member, means to guide said plate upon said frame, said plate having an opening, said member

6 having a portion to project through said opening to direct coins upon said member through said opening, said member being movable independently of said plate, and means to move said plate with said member after said projection has been drawn into said opening.

19. In a vending machine, the combination of a frame having a wall, a lever pivotally carried by said frame, a member movable relatively to said frame and opposed to said lever, said member having means to retain a coin in position to operate said lever, a plate between said wall and member, and means to guide said plate upon said frame, said plate having an opening, said member having a portion to project through said opening to direct coins upon said member through said opening, said member being movable independently of said plate, said plate having spaced projections, said member having projections in such spaces adapted to permit the member to have independent movement and to move said plate in opposite directions.

20. In a vending machine, the combination of a frame having a wall, a lever pivotally carried by said frame, a member movable relatively to said frame and opposed to said lever, said member having means to retain a coin in position to operate said lever, a plate between said wall and member, means to guide said plate upon said frame, said member being movable independently of said plate, said plate having an opening, said member having a portion to project through said opening to direct coins upon said member through said opening, said plate having spaced projections, said member having projections in such spaces adapted to permit the member to have independent movement and then to move said plate in opposite directions, said wall having an opening to admit the first named projecting portion of said member.

21. In a vending machine, a movable member, a plate adjacent to said member and provided with an opening, said member having a projection adapted to pass through said opening to direct a coin upon said member, said member having movement relatively to said plate to permit withdrawal of said projection from beyond said plate, and means to cause said plate to move with said member.

22. In a vending machine the combination of a frame having a wall, a plate spaced from said wall for the passage of coins therebetween, a movable member, said plate having an opening, said member having a projection adapted to pass through said opening into the space between said plate and wall to direct a coin upon said member, said member having movement relatively to said

plate to permit withdrawal of said projection beyond said plate, and means to cause said plate to move with said member.

23. In a vending machine the combination of a movable member, a plate adjacent to said member and provided with an opening, means to direct a coin upon the member through said opening, a finger movably carried by said plate above said member and having a portion adapted to engage a coin, a wall spaced from said plate, opposing the finger, said finger having a portion normally in said space adapted to engage a coin, and means to limit movement of the finger in the absence of articles from the machine to prevent coins from passing through said opening in the plate.

24. In a vending machine the combination of a movable member, a plate adjacent to said member and provided with an opening, means to direct a coin upon the member through said opening, a finger movably carried by said plate above said member and having a portion adapted to engage a coin, a wall spaced from said plate, said finger having a pair of spaced projections adapted to pass through an opening in said plate, one of said projections being above the other, one of said projections being normally in the path of coins through said space to cause tilting of said finger upon engagement of a coin or token therewith to cause the other of said projections to enter said space, to temporarily retain an apertured token against said wall, and means to move said plate relatively to said wall to release tokens caught upon one of said projections.

25. In a vending machine the combination of a movable member, a plate adjacent to said member and provided with an opening, means to direct a coin upon the member through said opening, a finger movably carried by said plate above said member and having a portion adapted to engage a coin, a wall spaced from said plate, said finger having a pair of spaced projections adapted to pass through an opening in said plate, one of said projections being above the other, one of said projections being normally in the path of coins through said space to cause tilting of said finger upon engagement of a coin or token therewith to cause the other of said projections to enter said space, to temporarily retain an apertured token against said wall, means to move said plate relatively to said wall to release tokens caught upon one of said projections, and movable means spaced from said plate to engage said finger to limit its movement by a coin or token.

26. In a vending machine the combination of a frame having a wall, a member movable relatively to said frame, a plate between said wall and member providing a

space therebetween, means to guide said plate upon said frame, said plate having an opening, said member having a portion to project through said opening into said 5 space to direct coins upon said member through said opening, said member being movable independently of said plate, said plate having a second opening, a finger pivotally carried by the plate and provided 10 with projections adapted to pass through

the last named opening to engage coins or tokens in said space to temporarily retain an apertured token against said wall.

Signed at New York city, in the county of New York, and State of New York, this 15 19th day of December, A. D. 1914.
